FIG. 3.

INVENTOR

Frederick M. Furber
By his Attorney
Nelson W. Howard

UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

MACHINE FOR USE IN REPAIRING ENAMELED LEATHER.

Application filed April 19, 1919. Serial No. 291,235.

To all whom it may concern:

Be it known that I, FREDERICK M. FURBER, a citizen of the United States, residing at Revere, in the county of Suffolk and State 5 of Massachusetts, have invented certain Improvements in Machines for Use in Repairing Enameled Leather, of which the following description, in connection with the accompanying drawings, is a specification, like 10 reference characters on the drawings indicating like parts in the several figures.

This invention relates to machines for use in the manufacture of boots and shoes and is herein illustrated as embodied in a machine 15 designed to prepare the injured tips of enameled shoes for the repairing of the enamel.

In the manufacture of shoes having patent or enameled leather tips, the enamel is often 20 cracked during the pulling over and lasting operations. To repair the cracked enamel, it is customary to remove enamel from about the cracks and apply size to the exposed surface of the leather preparatory to re- 25 enameled these surfaces by means of a "tip repairing" machine.

Hitherto it has been customary to employ a scouring wheel or a canvas covered wheel to scour off roughly or to burn off roughly the 30 enamel about a crack, this operation leaving an exposed surface bounded by a more or less abrupt shoulder. The shoulder was next beveled by a manual scouring operation, very fine sandpaper being used. Next a 35 coating of size was manually applied, and finally the size was brushed in to provide a smooth finished surface to receive the repair enamel. The general object of the present invention is to provide in one ma- 40 chine mechanism by which all of this preparatory work may be done more rapidly, with a saving of sizing material, and with an improvement in the result.

To this end the illustrative machine comprises a roughing-out tool in the form of a 45 rotary canvas covered or abrasive covered wheel for removing the enamel from about a crack, a smoothing tool in the form of an oscillating wheel having a cover of fine ab- 50 rasive material for beveling the shoulder which results from the action of the roughing-out tool, a size-applying brush to which size may be fed in measured quantity, and a rotary brush for brushing in the size. With

such a machine the operator may completely 55 prepare the tip of a shoe for the subsequent repairing operation.

The cover of the oscillating smoothing wheel rapidly becomes worn or filled with dirt in the locality which is in engagement 60 with the work, and a construction is therefore provided whereby the angular position of the wheel with respect to the oscillating shaft upon which it is mounted may be varied at any time to bring any selected 65 locality on the abrasive cover into operative position. This selective possibility is particularly advantageous in a machine of the type of the present one, since the dirt or dust which renders a locality on the cover 70 unfit for further use is often shaken out more or less after the locality has been moved to inoperative position, in which case the locality may be returned directly to operative position by a simple manual adjust- 75 ment.

Formerly the size has been applied by means of a hand brush which was dipped into a receptacle containing size and applied to the exposed surface of the leather, such 80 procedure resulting in waste of the size and in non-uniform applications. In the present machine the stationary brush to which the operator presents the work receives size from a tank, the size being supplied in small 85 measured quantities so that the right amount will be applied to the work.

These and other features of the invention will be described as embodied in an illustrative machine and pointed out in the ap- 90 pended claims.

Referring now to the accompanying drawings,

Fig. 1 is a view in front elevation of the upper and operating portions of a machine 95 constructed in accordance with the present invention, parts being broken away better to disclose certain mechanism;

Fig. 2 is a skeleton view in transverse section through the head of the machine on 100 the line 2-2 of Fig. 1 but with certain parts omitted;

Fig. 3 is a fragmentary perspective view of the oscillating smoothing wheel and the mechanisms for adjusting and driving it; 105

Fig. 4 is a section on the line 4-4 of Fig. 1 showing the liquid enamel feeding means.

The machine frame comprises the usual

floor-supported standard 2 upon the upper end of which is supported a blower 4 with the interior of which hoods 6 and 8 are connected in the usual manner by a passageway 5 which leads into the center of the blower casing. The vanes 11 of the blower are fast to a shaft 38, presently to be referred to, and are rotated by said shaft in a counter-clockwise direction as viewed in Figure 1. 10 The blower has two terminals 7 and 9 which face respectively in opposite directions; and a cap 5 is provided which may be placed over either terminal to close it. With the cap over the terminal 9, the blower will suck in air through the hoods and deliver it through the terminal 7. If now the cap is removed from the terminal 9 and placed over the terminal 7, the blower will suck in air as before but will deliver it through the terminal 15 9. It is usual in shoe factories to run an exhaust or waste pipe along one side of a room and to arrange along that side those machines which require the removal of dust, chips or other refuse. With the construction 20 which has just been described, the present machine may be properly placed on that side of the room along which the exhaust system is located without turning the machine around and without supplying any 25 extra connecting pipe. It is necessary merely to place the cap 5 on the proper terminal and to connect the other terminal to the factory system.

At the front of the blower 4 between the 30 hoods 6 and 8 a gear casing 10 outstands from the head of the machine and is connected with the hoods by axially offset tubular bearings 12 and 14 extending in substantial parallelism. A rotatable tool shaft 16 35 extends from the casing 10 through the uppermost bearing 12 and into the hood 6 where it carries a cloth covered or an abrasive covered wheel 18 of suitable construction and adjacent thereto a brush 20. A 40 second tool shaft 22, sustained in a plane substantially parallel to that of the first tool shaft with the ends of the shafts 16 and 22 within the gear casing 10 in overlapping relation, extends from casing 10 in the opposite 45 site direction through the lower bearing 14 and into the hood 8. A scouring wheel 24 is mounted within this hood on shaft 22 to turn with said shaft. As shown, wheel 24 is formed with a yielding peripheral surface 50 and is provided with a hollow hub 26 fastened to the shaft 22 by a set screw. This hub is extended out beyond the end of the shaft to form a handle 28. The periphery of wheel 24, which is the smoothing tool, is 55 partially covered by a belt 30 of abrasive material such as fine sandpaper, the upper end of the belt being carried on and guided by a flanged spool or idle pulley 32 having outstanding spindles 34, one of which may 60 serve as a handle for inserting the opposite

spindle in or withdrawing it from a bearing formed in the upper end of a bracket 36 standing from the head 4 when replacing a worn belt 30 with a fresh one. The bracket 36 is pivoted at its lower end to the frame 70 of the machine and is constantly urged by a spring (not shown) in a direction to maintain the belt taut.

The axially offset parallel shafts 16 and 22 are rotated and oscillated, respectively, 75 through connections from the power driven main shaft 38 extending at right angles to the tool shafts 16 and 22 from the rear of the machine to a point adjacent to the overlapping ends of the tool shafts and within 80 the gear casing 10, said power shaft having at its rear end the usual fast and loose pulleys, indicated generically at 40, Fig. 1, driven by a belt connection 42 from the usual factory line shaft.

Adjacent to its forward end the shaft 38 carries a helical gear 44 meshing with a similar gear 46 on the inner end of tool shaft 16 for rotating said tool shaft. Beyond the hub of gear 44, the shaft is provided with spaced annular flanges 48 and an intermediate eccentric portion 50, the forward flange 48 forming the end of the shaft and lying adjacent to the second tool shaft 22.

A yoke 52 has a curved lower face embracing the eccentric 50 and a flat upper face which supports a sliding semi-cylindrical bearing block 54 having an abutment flange 56 at one end. Resting on this block is the curved lower face of an arm 58 extended forwardly and formed with a bifurcated bearing including a sleeve 60 loosely journaled on the tool shaft 22 and having one end formed with clutch teeth 62. This bifurcated member is held against lengthwise 100 movement on the tool shaft by a block 64 fixed to the gear casing 10 and extending between its furcations. A coiled spring 66, interposed between the cover of gear casing 10 (Fig. 1) and the arm 58, serves to hold 105 the arm against bearing block 54, and the bearing block against the flat upper face of the yoke 52 as well as to hold the latter against the eccentric.

It will be evident that rotation of shaft 115 38 will cause yoke 52, block 54 and the contacting rear end of arm 58 to rise and fall, thereby oscillating the sleeve 60 on the tool shaft 22. This shaft is normally connected to the sleeve 60 to oscillate therewith by 120 means of a toothed clutch collar 68 fastened to shaft 22, a spring 61 (Fig. 1) being employed to hold the shaft so that the collar 68 will be in clutching engagement with the teeth 62. The tool shaft 22 with the attached hub 26 and clutch collar 68 may 125 be moved endwise in its bearings (to the left in Fig. 1) by pushing in on handle 28 to disengage the shaft temporarily from the sleeve 60 so as to permit the wheel 24 and 130

belt 30 to be turned by handle 28 to bring a fresh portion of the belt 30 over the working area of the periphery of wheel 24 when the portion of the belt previously at 5 the point becomes worn and ineffective from repeated scouring oscillations. It should be particularly noted that after the teeth 62 have been disengaged the handle 28 may be turned to any extent in either direction 10 so that any selected locality on the belt 30 may be brought into operative position. It is thus possible to pick out any selected locality on the belt and bring it immediately into operative position. It should be noted 15 too that the oscillation of the wheel 24 imparts to the working portion of the belt a motion which simulates closely the hand operation of rubbing back and forth, such a movement having been found desirable 20 to produce the desired result.

It frequently happens that the cracks appearing in patent or enamel leather of the toe portion of a shoe, for example, extend to the belt crease and cannot be reached by 25 the usual scouring wheel or belt. I have therefore provided a small abrasive hand tool which is arranged to be power operated, the power actuated connections being such that the tool is disconnected from 30 the power drive when the tool is not in use. To this end a journal block 70 (Fig. 2) is fixedly secured to the upper part of the casing of the blower 4 and is formed with an opening adjacent to its front end. 35 A bearing sleeve 72 extends from beyond the rear end of the journal block through a bore in the block to the rear wall of the opening therein. A shaft 74 is journaled in the sleeve and has its front end projecting into said opening and socketed to 40 receive and rotate the squared end of a tool spindle 75, which, forwardly of said squared end is journaled in the front end of the block 70 and connected by a flexible 45 shaft 76 to the spindle 78 of a rotatable hand tool 79 which, as shown, consists of a small disk of abrasive material.

The socket in the shaft 74 is of a length to permit lengthwise movement of the shaft 50 relatively to the end of the spindle 75. A pulley 80 is mounted and freely rotatable on the rear end of the sleeve 72 and is constantly driven by a belt connection to a pulley 82 fixed to the main drive shaft 38 55 as seen in Fig. 2. The pulley 80 at its rear side is formed with a clutch face with which a friction clutch disk 84 mounted on the rear end of shaft 74 may co-operate. The shaft 74 is movable lengthwise in its bearings to connect the shaft and clutch disk 84 60 with and disconnect it from the driving pulley 80. This movement of the shaft is effected through movement of an operatively connected tool support.

65 Accordingly, an arm 81 is bifurcated to

embrace the top of block 70 above the opening therein and is pivotally mounted thereon by a pivot pin 82. The forward end of arm 81 is provided with spaced sockets 83 receiving the rear ends of a bail 86 which 70 extends downwardly and forwardly and upon the cross-bar of which the flexible shaft 76 rests when the hand tool is not in use. The rear end of the arm 81 is provided with an extension 88 to which one end 75 of a coiled spring 90 is anchored, the other end of said spring being anchored to the top of block 70. The weight of the flexible shaft 76 and its tool 79 against the cross-bar of the bail 86 will swing the forward end 80 of arm 81 downwardly, and the spring 90 will swing said end upwardly when the weight is removed by the picking up by the operator of the hand tool and flexible shaft for use on the work. These movements of 85 the arm 80 are utilized to effect clutching and unclutching movements of the shaft 74.

The forward end of the shaft 74 extending within the opening in journal block 70 and shown in section in Fig. 2, is reduced in diameter providing a shoulder and has its extremity threaded. A collar 92 is mounted on the reduced end of the shaft between flange disks 94 of relatively large diameter, a nut 96 screwing on the threaded end of shaft 74 95 crowding the rearmost disk against the shoulder of shaft 74 and clamping the disks and collar to the shaft. A loose ring 98 concentric with collar 92 is confined between the disks 94 and at diametrically opposite 100 points is engaged and held between set screws 100 threaded into bores in the lower ends of legs 102 formed as downward extensions of the bifurcated arm 81 and located below the pivot 82 of said arm. The sleeve 105 98 has a loose fit over the collar 92 and does not rotate with the collar and shaft but may move them longitudinally since it is confined between the disks 94. When the operator drops the flexible shaft on the cross-bar of the bail 86, the forward end of arm 81 is automatically swung downwardly and the legs 102 and sleeve 98 are swung rearwardly as shown in Fig. 2, thereby sliding the shaft 74 rearwardly to disengage clutch 115 disk 84 from pulley 80. When the operator picks up the hand tool for use and thereby removes the weight of the flexible shaft and tool from the bail, the spring 90 automatically swings the arm 81 in a reverse direction; and, through the sleeve 98 and disks 94, slides the shaft 74 forwardly to bring its disk 84 into clutching engagement with the continuously rotating pulley 80.

At one side of the machine head, a bracket 125 104 (Fig. 1) extends upwardly and supports a reservoir or tank 106 in which liquid size is stored. At the lower end of the tank an outlet opening is provided to receive the end of a curved discharge pipe 108 which 130

is provided with a collar having laterally extending plates 110 formed with notches in their edges. Bolts extending from the face of the tank are received in these notches, 5 and wing nuts 112 engaging the bolts clamp the plates and feed pipe tightly to the tank. The described fastening means facilitates the connection of the discharge pipe to and its disconnection from the tank and permits 10 the discharge pipe and its attached parts to be readily removed and replaced when desired.

At the lower end of the discharge pipe a suitably constructed fluid applying member 15 such as a brush 114 is attached; and, interposed between this brush and the upper end of the discharge pipe, is a manually operable feed wheel shown in section in Fig. 4. The valve casing 116 is suitably bored to 20 receive and journal a rotary feed wheel 118 having a plurality of size receiving pockets 120 formed in its periphery. A spindle extends outwardly through the casing from this feed wheel and is provided with an operating handle 122. By giving successive partial turns to handle 122, the operator may cause successive pockets 120 to feed the size therein to the brush 114 as it is needed. The pockets 120 have very limited capacities so 25 that only a small amount of size is delivered at any time. In this connection it should be noted that the diameter of the pipe 108 and the spacing of the pockets is such that only one pocket is in delivering position at 30 any time. It is desirable that the brush 114 should be just damp with the liquid size, since only a small amount should be applied to the work; and the feed mechanism which has been described above, by permitting the 35 feed of small quantities only of the size, furnishes a satisfactory means for keeping the brush in the proper degree of dampness.

In the use of the described machine to 40 prepare a cracked enamel tip for the "tip repairing" machine, the operator presents the cracked portion of the tip to the wheel 18 which, if covered with cloth, will "burn" off the enamel in the area about the crack or, if covered with coarse sandpaper, will 45 scour it off, leaving in either case an area bounded by abrupt shoulders. The shoulders are now smoothed down by subjecting the appropriate portion of the leather to the fine sandpaper belt on the wheel 24 which 50 oscillates and thereby rubs the work. The action of the fine sandpaper belt 30 not only bevels the shoulder but smooths the exposed surface of the leather. There is left, however, a short nap which should be laid; and 55 the surface of buffed leather is always somewhat porous. The smoothed surface is, therefore, presented first to the brush 114, to receive a small amount of size, and then to the rotating brush 20 which lays the nap 60 and brushes in the size. The surface to be 65

re-coated with enamel is thus smoothed and filled so that it may be properly re-enamed. When a portion of the cracked area is inaccessible to the wheel 18 and belt 30, as for example when a crack extends into the rand 70 crease, the tool 79, which is provided with a disk of fine sandpaper, is used to prepare the surface for the coating of size.

Although the invention has been set forth as embodied in a machine for preparing cracked tips of enameled shoes for the re-enameling operation, it should be understood that the invention is not limited in the scope of its application to the particular machine which has been shown and described.

Having described my invention, what I claim as new and desire to secure by Letters Patent of the United States is:

1. In a machine of the class described, 85 the combination of a power driven shaft, two tool carrying shafts, rubbing tools secured to said shafts, operating connections from said power driven shaft to one of said tool shafts constructed and arranged to rotate said tool shaft and connections including an eccentric on the power shaft for oscillating the other of said tool shafts about its axis.

2. In a machine of the class described, 95 the combination of a power driven shaft, two tool carrying shafts sustained in substantially parallel planes, a rotating driving connection from said power shaft to one of said tool shafts, and connections from said 100 power shaft to the other of said tool shafts effective to oscillate said tool shaft.

3. In a machine of the character described, the combination of a power driven shaft, two tool carrying shafts, and operating connections from said power shaft to each of said tool shafts constructed and arranged to rotate one of said tool shafts and to oscillate the other of said tool shafts, one of said tool shafts being arranged for 110 manually effected lengthwise movement to disconnect said tool shaft from said power shaft operating connections.

4. In a machine of the class described, the combination of a power driven shaft, two 115 tool carrying counter shafts sustained in substantially parallel planes with adjacent ends overlapping, a rotating driving connection from said power shaft to the overlapping end of one of said counter shafts, 120 and connections from said power shaft to the overlapping portion of said other counter shaft effective to oscillate said other counter shaft.

5. In a machine of the character described, the combination of a power driven shaft, two tool carrying counter shafts, leather working tools secured to said counter shafts, a rotary driving connection between said power shaft and one of said 125 130

counter shafts, and connections from said power shaft to the other of said counter shafts effective to oscillate said other counter shaft about its axis.

- sively to removal of the tool from said support, and means responsive to the movement of the tool support for connecting said second tool shaft with the main driving shaft.
- 5 14. In a machine of the class described, the combination with a power driven main shaft, a tool carrying shaft operatively connected to said main shaft for continuous actuation, a selectively operable second tool shaft, a hand tool having a flexible driving connection with said second shaft, a support for the hand tool when inoperative arranged to be moved responsively to the weight of the tool when supported and to 10 the release of the weight when the tool is removed, operating connections between the main driving shaft and said second tool shaft including a clutch mechanism, and means for operating said clutch mechanism 15 to connect said second shaft with and to disconnect it from said main shaft, actuated responsively to the movement of the tool support.
16. In a machine of the class described, the combination of a rotatable tool shaft 20 mounted for lengthwise movement in reverse directions, a driving element for said shaft, power driven means for continuously actuating said element, co-operating means 25 on said driving element and tool shaft positioned by said lengthwise movements of the shaft to connect said shaft with and to disconnect it from the driving element, a hand tool, a flexible driving connection between 30 said tool and shaft, and a support for the tool when inoperative movable responsively to the placing of the tool on and the removal of the tool from said support to move the shaft longitudinally in reverse directions to connect and disconnect said shaft 35 and driving element.
17. In a machine of the class described, the combination of a rotatable tool shaft 40 mounted for lengthwise movement in reverse directions, a driving element for said shaft in concentric relation to and freely revolvable about said shaft and having a clutch member, a co-operating clutch member connected to and movable longitudinally 45 with said shaft to connect said shaft with and to disconnect it from said driving element, a hand tool, a flexible driving connection between said tool and the tool shaft, a support for the tool when inoperative 50 movable in different directions responsively to the placing of the tool on and the removal of the tool from said support, and means actuated by said movements of the support for moving the shaft longitudinally to connect and disconnect the shaft and driving element.
- 55 18. In a machine of the class described, the combination of a power driving shaft, a tool shaft, a wheel fixed to said tool shaft, an idle pulley supported in determinate relation to said wheel, an idle pulley supported in determinate relation to said wheel, a belt of abrasive material about the peripheries of said wheel and pulley, and connections between said driving shaft and the tool shaft effective to oscillate said tool and its abrasive covered wheel, said connections including a rocking member journaled on said tool shaft and having a clutch portion, and a co-operating clutch member on said shaft, said tool shaft being constructed and arranged for successive manually effected longitudinal and rotary movements respectively to disconnect the shaft and its clutch member from said rocking member and to rotate said wheel to bring a fresh portion of the abrasive belt into operative position.
- 60 19. In a machine of the class described, a scouring wheel, an abrasive element supported thereby, a member for oscillating the wheel about its axis to cause the abrasive element to rub the work, and manually operable means for connecting the wheel in a different angular position with the member to bring a fresh portion of the abrasive element to a working position on the wheel.
- 65 20. In a machine of the class described, a belt of stock-treating material for said wheel extending about the peripheries of the wheel and pulley, connections between the driving shaft and the tool shaft effective to oscillate said tool shaft, and manually operable means for rotating said wheel and belt independently of the driving shaft to bring a fresh portion of the belt into operative position.
- 70 21. In a machine of the class described having, in combination, a tool, means for operating the tool, a hood partly enclosing the tool, and a blower connected with the hood, said blower comprising a casing having tangential terminals extending in different directions, and means for selectively closing the terminals.
- 75 22. In a machine of the class described having, in combination, a tool, means for operating the tool, a hood partly enclosing the tool, and a blower connected with the hood, said blower comprising a casing having tangential terminal pipes extending in different directions, and a cap for selectively closing one of the terminal pipes.
- 80 23. In a machine of the class described having, in combination, a tool, means for operating the tool, a hood partly enclosing the tool, and a blower connected with the hood, said blower comprising a casing having tangential terminal pipes extending in different directions, and a cap for selectively closing one of the terminal pipes.
- 85 24. A machine of the class described having, in combination, a tool, means for operating the tool, a hood partly enclosing the tool, and a blower connected with the hood, said blower comprising a casing having tangential terminal pipes extending in different directions, and a cap for selectively closing one of the terminal pipes.
- 90 25. A machine of the class described having, in combination, a tool, means for operating the tool, a hood partly enclosing the tool, and a blower connected with the hood, said blower comprising a casing having tangential terminal pipes extending in different directions, and a cap for selectively closing one of the terminal pipes.
- 95 26. A machine of the class described having, in combination, a tool, means for operating the tool, a hood partly enclosing the tool, and a rotary blower on the machine having a casing connected with the hood, said blower casing being constructed and arranged for connection at its periphery with an exhaust pipe at either side of the machine.
- 100 27. In a machine of the class described, the combination of a driving shaft, a tool shaft, a wheel fixed on said tool shaft, an idle pulley supported in determinate relation to said wheel, a belt of abrasive material about the peripheries of said wheel and pulley, and connections between said driving shaft and the tool shaft effective to oscillate said tool and its abrasive covered wheel, said connections including a rocking member journaled on said tool shaft and having a clutch portion, and a co-operating clutch member on said shaft, said tool shaft being constructed and arranged for successive manually effected longitudinal and rotary movements respectively to disconnect the shaft and its clutch member from said rocking member and to rotate said wheel to bring a fresh portion of the abrasive belt into operative position.
- 105 28. In a machine of the class described, a belt of stock-treating material for said wheel extending about the peripheries of the wheel and pulley, connections between the driving shaft and the tool shaft effective to oscillate said tool and its abrasive covered wheel, said connections including a rocking member journaled on said tool shaft and having a clutch portion, and a co-operating clutch member on said shaft, said tool shaft being constructed and arranged for successive manually effected longitudinal and rotary movements respectively to disconnect the shaft and its clutch member from said rocking member and to rotate said wheel to bring a fresh portion of the abrasive belt into operative position.
- 110 29. In a machine of the class described, a belt of stock-treating material for said wheel extending about the peripheries of the wheel and pulley, connections between the driving shaft and the tool shaft effective to oscillate said tool and its abrasive covered wheel, said connections including a rocking member journaled on said tool shaft and having a clutch portion, and a co-operating clutch member on said shaft, said tool shaft being constructed and arranged for successive manually effected longitudinal and rotary movements respectively to disconnect the shaft and its clutch member from said rocking member and to rotate said wheel to bring a fresh portion of the abrasive belt into operative position.
- 115 30. In a machine of the class described, a belt of stock-treating material for said wheel extending about the peripheries of the wheel and pulley, connections between the driving shaft and the tool shaft effective to oscillate said tool and its abrasive covered wheel, said connections including a rocking member journaled on said tool shaft and having a clutch portion, and a co-operating clutch member on said shaft, said tool shaft being constructed and arranged for successive manually effected longitudinal and rotary movements respectively to disconnect the shaft and its clutch member from said rocking member and to rotate said wheel to bring a fresh portion of the abrasive belt into operative position.
- 120 31. In a machine of the class described, a belt of stock-treating material for said wheel extending about the peripheries of the wheel and pulley, connections between the driving shaft and the tool shaft effective to oscillate said tool and its abrasive covered wheel, said connections including a rocking member journaled on said tool shaft and having a clutch portion, and a co-operating clutch member on said shaft, said tool shaft being constructed and arranged for successive manually effected longitudinal and rotary movements respectively to disconnect the shaft and its clutch member from said rocking member and to rotate said wheel to bring a fresh portion of the abrasive belt into operative position.
- 125 32. In a machine of the class described, a belt of stock-treating material for said wheel extending about the peripheries of the wheel and pulley, connections between the driving shaft and the tool shaft effective to oscillate said tool and its abrasive covered wheel, said connections including a rocking member journaled on said tool shaft and having a clutch portion, and a co-operating clutch member on said shaft, said tool shaft being constructed and arranged for successive manually effected longitudinal and rotary movements respectively to disconnect the shaft and its clutch member from said rocking member and to rotate said wheel to bring a fresh portion of the abrasive belt into operative position.
- 130 33. In a machine of the class described, a belt of stock-treating material for said wheel extending about the peripheries of the wheel and pulley, connections between the driving shaft and the tool shaft effective to oscillate said tool and its abrasive covered wheel, said connections including a rocking member journaled on said tool shaft and having a clutch portion, and a co-operating clutch member on said shaft, said tool shaft being constructed and arranged for successive manually effected longitudinal and rotary movements respectively to disconnect the shaft and its clutch member from said rocking member and to rotate said wheel to bring a fresh portion of the abrasive belt into operative position.

scouring wheel, an abrasive element supported thereby, a drive shaft, connections between the drive shaft and the wheel effective to oscillate the wheel, and means for 5 rotating said wheel independently of the drive shaft to bring a fresh portion of the abrasive element into working position.

24. In a machine of the class described, a tool shaft having a scouring wheel, an abrasive element supported by the wheel, a drive shaft, a member actuated by the drive shaft effective to oscillate the tool shaft, and clutch members for securing the tool shaft 10 and member in different angular positions

to bring fresh portions of the abrasive ele- 15
ment to working position.

25. In a machine of the class described, a scouring wheel, an abrasive element supported thereby, an oscillating member for driving the wheel, means for connecting the 20 wheel in different angular positions with the member, and means whereby the wheel may be disconnected from the member, turned directly to any one of the positions and re-engaged with the member. 25

In testimony whereof I have signed my name to this specification.

FREDERICK M. FURBER.
